UNITED STATES PATENT OFFICE.

JOHN M. FEEDERS, OF BUFFALO, NEW YORK, ASSIGNOR TO FEEDERS MANUFACTURING COMPANY, INC., OF BUFFALO, NEW YORK, A CORPORATION OF NEW YORK.

RADIATOR UNIT.

1,397,625.

Specification of Letters Patent.

Patented Nov. 22, 1921.

Application filed February 20, 1920. Serial No. 360,207.

To all whom it may concern:

Be it known that I, JOHN M. FEEDERS, a citizen of the United States, residing at Buffalo, in the county of Erie and State of 5 New York, have invented new and useful Improvements in Radiator Units, of which the following is a specification.

This invention relates to a radiator unit which is so constructed that a plurality of 10 such units when assembled produce a core for radiators.

The object of this invention is to produce a unit of this character which when assembled with others to form a core will not slide 15 laterally out of place, and also provide a staggered water passage between adjacent units which increases the radiating efficiency, said units being also provided with integral wings which project into the air 20 passages and promote the radiation of heat from the water passing through the water passages.

In the accompanying drawings:

Figure 1 is a fragmentary elevation, 25 partly in section, of a radiator containing my improved units. Fig. 2 is a horizontal section taken on line 2—2, Fig. 1. Fig. 3 is a vertical section taken on line 3—3, Fig. 1. Fig. 4 is a perspective view of one of 30 the units.

Similar characters of reference indicate corresponding parts throughout the several views.

In its completed form the radiator comprises a plurality of tortuous water passages 35 10, preferably arranged vertically and a plurality of horizontal air tubes 11, 12 and 13 arranged between the water passages and extending from the front side to the rear 40 side thereof, said passages communicating at opposite ends with water boxes or headers of which one is shown for example at 14 in Fig. 1, while the air tubes open at their opposite end to the atmosphere, so that the 45 passage of the air through the air tubes carries away the heat of the water in the water passages or channels. The core or heat exchanging section of the radiator comprises a plurality of units each of which is constructed of a single strip of metal so as to 50 55 form two parallel air tubes 11 and 12 and a web 15 arranged between these tubes and formed integrally therewith, as shown in Fig. 4. The air tubes, as shown in Fig. 1, are hexagonal and the same are so arranged

relatively to each other that the two summits 20, 23 on diametrically opposite sides of each tube are arranged on a vertical line parallel with the general longitudinal direction of the water passages. Each of the 60 units is bent out of a single strip of metal to form triple corrugations on one side of the unit, double corrugations on the opposite side of the unit and two pairs of transverse walls. The triple corrugation of each unit 65 comprises the intermediate member consisting of the web 15 which forms two facets 16 tapering outwardly to a central longitudinal summit 17 in the form of a wedge, and two side members each consisting of two 70 facets 18, 19 tapering outwardly to a central longitudinal summit 20 in the form of a wedge. Each of the pair of corrugations on the opposite side of the unit is arranged diametrically opposite one of the 75 side members of the triple corrugations and forms two facets 21, 22, tapering outwardly to a central longitudinal summit 23 in the form of a wedge. Each pair of transverse walls consists of an outer transverse member 80 25 forming a facet which connects the outer longitudinal edges of one of the outer facets 19 of the triple corrugations and one of the outer facets 22 of the double corrugations, and an inner transverse member 24 forming 85 a facet which is connected at one of its longitudinal edges with the inner longitudinal edge of the inner facet 21 of one of said pair of corrugations while its other longitudinal edge engages with the base between the inner facet 18 of one of the side members of the triple corrugations and the adjacent facet 16 of the intermediate member of the triple corrugations. The opposite ends of the outer facets 19 of the side members of 90 the triple corrugations and of the outer facets 22 of the members of the double corrugations and of the outer wall members 25 are provided with lateral off-sets 95 26.

In the assembled condition of a plurality 100 of such units the outer facet 19 of one side member of the triple corrugations is opposite an inner facet 21 of one member of the pair of corrugations and the facets 16 on one side of the intermediate member and the 105 facet 18 on the adjacent side member of the triple corrugations are opposite the inner and outer facets 21, 22 of one of the double corrugations of an adjacent unit, which units however only engage each other along 110

the lateral offsets 26 and also along the summits 20 and 23. The outer walls 25 of each unit also are opposed to the corresponding outer walls 25 of adjacent units so that when 5 completely assembled the core of the radiator presents a honey-comb appearance. When thus assembled, a plurality of tortuous or zig-zag water passages or channels 10 are formed between adjacent units, which 10 lengthen the water course as compared with a straight channel and improves the radiating efficiency accordingly. Each unit not only forms two air passages 11 and 12 but the intermediate members of the triple corrugations of adjacent units together also 15 form additional air tubes 13. The several units engage each other with a wedging action owing to the tapering formation of the coöperating surfaces, thereby operating to 20 center the units relatively to each other and preventing the units from sliding laterally out of place while being assembled and permitting the front and rear ends of the units to be easily soldered, so as to seal the water 25 passages and connect the several units with each other.

Furthermore, by forming the hexagonal tubes so that each air tube has a wedge formation on its diametrically opposite sides 30 and on a line parallel with the general direction of the water passages a minimum contact of metal between adjacent units is obtained, the engagement of each unit in this instance with an adjacent unit occurring 35 ring at not more than three places, thereby obtaining the maximum radiating efficiency for the amount of metal employed.

In order to further increase the radiating efficiency of the unit each of the inner walls 40 of a pair is provided with a plurality of radiating wings or fins 27 which are punched or cut out of these walls so as to remain integrally connected therewith and project laterally into the air path, thereby 45 causing the air to be intercepted and cause the same to carry away the heat from the water in the channels more efficiently.

I claim as my invention:

1. A radiator unit comprising a strip of 50 sheet metal bent to form a triple corrugation on one of its sides, a double corrugation on its opposite side and two pairs of transverse walls, said triple corrugations consisting of a central corrugation and two side 55 corrugations each of which tapers outwardly to a central longitudinal summit, each of said pairs of corrugations being arranged diametrically opposite one of the side members of the triple corrugations and tapering 60 outwardly to a central longitudinal summit and each pair of transverse walls having an outer wall connecting the corresponding outer longitudinal edges of one of the pairs 65 of corrugations and the adjacent side member of the triple corrugation, and an inner wall connected with the inner longitudinal

inner wall connected with the inner longitudinal edge of one of the pair of corrugations and engaging its opposite edge with one of the longitudinal bases between the intermediate and one of the side members 70 of the triple corrugations.

2. A radiator unit comprising a strip of sheet metal bent to form a triple corrugation on one of its sides, a double corrugation on its opposite side and two pairs of transverse walls, said triple corrugations consisting of a central corrugation and two side corrugations each of which tapers outwardly to a central longitudinal summit, each of said pairs of corrugations being 80 arranged diametrically opposite one of the side members of the triple corrugations and tapering outwardly to a central longitudinal summit and each pair of transverse walls having an outer wall connecting the corresponding outer longitudinal edges of one of the pairs of corrugations and the adjacent side member of the triple corrugation, and an inner wall connected with the inner longitudinal edge of one of the pair 90 of corrugations and engaging its opposite edge with one of the longitudinal bases between the intermediate and one of the side members of the triple corrugations, the outer walls of each pair and adjacent facets 95 of the triple and double corrugations being offset laterally at opposite ends of the unit.

3. A radiator unit comprising a strip of sheet metal bent to form a triple corrugation on one of its sides, a double corrugation on its opposite side and two pairs of transverse walls, said triple corrugations consisting of a central corrugation and two side corrugations each of which tapers outwardly to a central longitudinal summit, each of said pairs of corrugations being arranged diametrically opposite one of the side members of the triple corrugations and tapering outwardly to a central longitudinal summit and each pair of transverse walls having an outer wall connecting the corresponding outer longitudinal edges of one of the pairs 105 of corrugations and the adjacent side member of the triple corrugation, and an inner wall connected with the inner longitudinal 110 edge of one of the pair of corrugations and engaging its opposite edge with one of the longitudinal bases between the intermediate and one of the side members of the triple corrugations, the outer walls of each pair and adjacent facets of the triple and double corrugations being offset laterally at opposite ends of the unit and adapted to engage corresponding offsets on adjacent units to 115 form water passages therebetween and the corrugations of each unit being adapted to cooperate with the summits of adjacent units for producing tubes between the intermediate corrugations thereof.

4. A radiator unit comprising a plurality 120

of parallel tubes which have adjacent sides connected and which are constructed of a single strip of metal, the upper and lower sides of said tubes being tapered upwardly and downwardly to a longitudinal central line, the inner walls of said tubes being provided with radiating wings.

5. A radiator unit comprising a plurality of parallel tubes which have adjacent sides

connected and which are constructed of a single strip of metal, the upper and lower sides of said tubes being tapered upwardly and downwardly to a longitudinal central line, the inner walls of said tubes being provided with radiating wings formed integrally therewith and projecting laterally therefrom.

JOHN M. FEDDERS.
